UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,445; dated August 30, 1881.

Application filed July 20, 1881. Term of patent 3½ years.

To all whom it may concern:

Be it known that I, THOMAS J. STEARNS, of Boston, in the county of Suffolk and State of Massachusetts, have invented a certain new and original Design for Carpets, of which the following is a specification.

My present design is fully shown in the accompanying photographic illustration, forming part of this specification.

10 The design consists of the figure A, resembling an arched trellis, having flowering plants and foliage intertwined therewith and supported thereon, and the figures B and C, composed of geometric ornamentation commingled

15 with representations of foliage and flowers, the said figures arranged as shown and disposed upon a plain ground.

I claim—

The design for a carpet, substantially as herein shown and described.

In testimony whereof I have signed my name to this specification, in the presence of two subscribing witnesses, this 9th day of July, A. D. 1881.

THOMAS J. STEARNS.

Witnesses:

D. MCNAIR,
WILLIAM SCHMIDT.
